UNITED STATES PATENT OFFICE.

GABRIEL F. RAY, OF ROSWELL, NEW MEXICO.

DISH-WASHER.

1,141,414.

Specification of Letters Patent.

Patented June 1, 1915.

Application filed March 17, 1914. Serial No. 825,347.

To all whom it may concern:

Be it known that I, GABRIEL F. RAY, a citizen of the United States, residing at Roswell, in the county of Chaves and State 5 of New Mexico, have invented a new and useful Dish-Washer, of which the following is a specification.

The present invention appertains to a dish washer or liquid agitator, and aims to 10 provide a novel and improved contrivance of that character.

It is the object of the present invention to provide a dish washer including in combination with a receptacle or pan, and dish 15 holding or supporting means therein, novel agitating means within the receptacle for spraying the water against the dishes to cleanse the same.

Another object of the present invention 20 is to provide novel means for actuating the agitating means.

It is also within the spirit of the present invention, to provide an appliance of the nature indicated, which will be comparatively 25 simple, compact and inexpensive in construction, as well as being simple, convenient, serviceable, practical and efficient in its use.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

The invention has been illustrated in its 40 preferred embodiment in the accompanying drawing, wherein:-

Figure 1 is a vertical central section of the improved apparatus. Fig. 2 is a fragmental sectional view, taken on the line 45 2-2 of Fig. 1.

In carrying out the present invention, there is provided a receptacle or container 1 of any suitable character, which is preferably, although not necessarily, of inverted

frusto-conical form, in order that its sides 50 will be inclined. The receptacle or pan 1 is provided with a cover 2, which is divided diametrically into two sections 3, the adjoining edges of the cover sections being provided with coöperating notches 4 forming 55 an opening, centrally of the cover and receptacle.

A bearing 5 is carried by the cover 2, the bearing being provided with a peripheral groove 6, which groove receives the edge 60 portions of the cover sections 3 defined by the notches 4, whereby the notches 4 embrace the hub portion of the bearing, while the flanges of the bearing overlap the upper and lower faces of the cover sections. It is 65 evident that the bearing may be readily applied to and removed from the cover, when the cover sections are separated. The cover sections may normally be locked together by any well known means, which it is not 70 necessary to illustrate or describe in detail.

The agitating means includes an upright shaft or spindle 7 journaled through the bearing 5 and having its lower end journaled within a socket bearing 8 secured 75 upon the bottom of the receptacle 1, the shaft 7 being arranged axially or centrally of the receptacle. Disposed within the receptacle 1 and surrounding the shaft 7 is an inverted funnel-shaped or frusto-conical 80 rotor 9, the same tapering downwardly, or increasing in diameter upwardly. The upper and lower ends of the rotor 9, are open, the rotor being hollow, and preferably being constructed of sheet metal or other suitable material. The rotor 9 is carried by the shaft 7, by means of upper and lower spiders 10 and 11 attached to the upper and lower ends of the rotor and the shaft 7 within the receptacle. The arms or wires of 90 the spiders 10 and 11 are preferably inclined, so as to be attached to the shaft 7 beyond the ends of the rotor. The lower end of the rotor, which is provided with a constricted or relatively small opening, is 95 spaced above the bottom of the receptacle, while the upper or larger end of the rotor is spaced below the cover 2. The upper or

larger end portion of the rotor is provided with apertures or perforations 12, the lower end portion of the rotor being imperforate.

The actuating means for the agitator, embodies a coupling bearing 13 rotatably receiving the upper end of the shaft 7 which protrudes above the cover 2, and a removable stationary upright shaft or spindle 14 has its lower end received by the coupling bearing 13 and is provided at its upper end with a handle or handhold 15. The lower end of the spindle 14 is preferably secured within the bearing 13 by means of a set screw 16, or its equivalent. The spindle 14 carries a lateral pindle 17 upon which is journaled a power or driving bevel gear 18, of relatively large diameter, and having a crank handle 19. The driving gear 18 meshes with a bevelled pinion 20 keyed upon the upper end portion of the agitator shaft 7.

The dish rack or holder, which is disposed within the receptacle 1, embodies an annular inverted frusto-conical member 21, which is of foraminous or reticulated material, to permit the ready passage of water therethrough. The member 21 is of such diameter, as to be disposed intermediate the rotor 9 and the side walls of the receptacle 1, the member 21 surrounding the rotor, and having a lower outturned annular shelf portion 22, which is also foraminous or reticulated. The annular rack member 21 is also provided at its lower end with legs 23 seating upon the bottom of the receptacle 1, to support the rack above the bottom of the receptacle, the shelf 22 extending to the side walls of the receptacle, for supporting the dishes around the side walls of the receptacle, surrounding the annular rack member 21. The rack member 21 in circling the rotor, provides an annular pocket above the shelf portion 22 for receiving the dishes, and also provides a clearance between the rotor and rack, for the proper action of the water.

In use, when the cover or one section thereof, is removed from the receptacle 1, the dishes may be readily placed upon the shelf portion 22 of the rack, and the dish water may be readily poured into the receptacle. In order to establish a most effective cleansing action, the receptacle 1 should only be partially filled with water. After the cover has been placed upon the receptacle, and the several parts assembled properly, the operator may conveniently actuate the rotor or agitator 9, by holding the spindle 14 in one hand, through the medium of the hand hold 15, and by rotating the driving gear 18, through the medium of the crank handle 19. In this manner, the shaft 7 will be rotated at a high velocity, in order that the water within the rotor or agitator 9 will, due to centrifugal action, rise within the rotor, and be discharged through the apertures 12 and over the rim or upper end of

the rotor, and thence outwardly against the dishes. In this manner, the water is elevated within the rotor and is discharged radially through the upper portion of the rotor in a spray, the jets impinging against the dishes with sufficient force to cleanse the same properly. As the operation is continued, a circulation of water will be established upwardly through the rotor, thence outwardly against the dishes, due to the centrifugal action created by the rotor, the water then flowing downwardly from the dishes to the bottom of the receptacle and to the lower end of the rotor to be sucked up into the rotor.

After the dishes have been cleansed, the dish water may be discharged or drained out, and fresh water may then be poured into the receptacle 1, whereby when the agitator is again operated, the dishes may be rinsed. After the rinsing operation, the dishes may be removed and permitted to dry.

It will be evident that the several parts of the present apparatus may be readily separated, for the purpose of cleaning, repair or replacement, the present device being comparatively simple and inexpensive, but nevertheless, being practical and efficient in operation.

The present device may be constructed on a smaller scale, to serve as an egg and cream beater, or the like, in which event, the wire rack or holder within the receptacle, is eliminated or removed.

From the foregoing, the several advantages and capabilities of the present device will be obvious without further comment, it being noted that the objects aimed at have been carried out satisfactorily.

Having thus described the invention, what is claimed as new is:—

1. An agitating device comprising a receptacle, a cover therefor including separable sections, the cover sections having co-operating notches forming an opening, a bearing disposed within the said opening and having a peripheral groove engaging the edge portions of the said notches and providing flanges overlapping the top and bottom of the cover sections, a bearing secured upon the bottom of the receptacle, a shaft journaled through the first mentioned bearing and having its lower end journaled within the second mentioned bearing, and an agitator carried by the shaft within the receptacle.

2. An agitating device comprising a receptacle having a cover, an upright rotary shaft journaled through the cover and having its lower end journaled upon the bottom of the receptacle, an agitator carried by the shaft within the receptacle, an upright spindle having a handle at its upper end, the lower end of the spindle and the upper end of the shaft having inter-engageable means

for enabling the spindle to be detachably mounted upon the shaft, an actuating mechanism carried by the spindle, and means carried by the shaft engageable with the said mechanism when the spindle is assembled with the shaft, to enable the shaft to be rotated.

In testimony that I claim the foregoing as my own, I have hereto affixed my signature in the presence of two witnesses.
